SPRING CLAMP

Arley D. Carpenter, Los Angeles, and John A. Carpenter, North Hollywood, Calif.

Application April 20, 1951, Serial No. 222,029

1 Claim. (Cl. 24—257)

1

This invention relates to clamps for clamping cables, electrical conduits, pipe and the like on hanger bars, supported in buildings, ships and elsewhere, and the general object of the invention is to provide a novel spring clamp for detachably clamping cables and the like on such hanger bars, whereby cables and the like may be more readily clamped on a hanger bar or unclamped therefrom without the use of tools.

A more particular object is to provide an improved clamp of the character stated, which is very simple, inexpensive and efficient in operation.

Other objects and advantages will appear hereinafter as this specification progresses.

The invention is illustrated in the annexed drawing which forms a part of this specification and in which:

Fig. 1 is a side elevation of two hanger bars supported on brackets, with a cable shown clamped on said hanger bar by my invention.

Fig. 2 is a top plan view of Fig. 1.

Fig. 3 is a bottom plan view of Figs. 1 and 2.

Fig. 4 is a transverse vertical section taken on line 4—4 of Fig. 1.

Fig. 5 is a transverse vertical section taken on line 5—5 of Fig. 1, showing my invention in the act of being applied to the hanger bar and the cable, for detachably clamping the cable on the hanger bar.

Fig. 6 is a perspective of my invention.

Referring more particularly to the drawing, in which the same parts are designated by the same reference numerals in all of the views, our invention comprises a spring clamp designated 1 in its entirety formed of a single piece of spring steel wire 2 bent intermediate its ends into a coil spring 3, from the ends of which spring said wire is bent laterally into a pair of arms 4 and 5 extending outwardly horizontally from said spring in opposite directions, and from the outer ends of which arms 4 and 5 said wire 2 is bent upwardly into a pair of upstanding vertical arms 6 and 7 respectively, the upper ends of which vertical arms 6 and 7 being bent in opposite directions forwardly and backwardly into a pair of hooks 8 and 9 respectively.

My invention is particularly useful for detachably clamping cables 10, electric conduits and pipe on a hanger bar 11, which may be supported at its ends on lugs 12 extending laterally from a vertical bracket 13, secured on a wall or other support. The ends of the hanger bar 11 may be detachably secured at its ends to lugs 12 on two brackets 13 by means of two screws 14 and two

2

nuts 15 threaded on said screws, which screws extend downwardly through the ends of the hanger bar 11 and the bracket lugs 12 on which the ends of the hanger bar rests, with the heads of said screws resting upon the upper side of said hanger bar and the nuts 15 threaded on the lower ends of said screws tightly against the lower sides of said lugs 12. The hanger bar 11 may be a channel bar formed with an upper horizontal base wall 16 and two vertical side walls 17 depending from the side edges, respectively, of said upper horizontal base wall 16. The hanger disclosed herein including the hanger bar 11, the brackets 13 and the screws 14 and nuts 15 for detachably securing the ends of said bar to the lugs 12 of said brackets 13 form the subject matter of my co-pending application Ser. No. 222,028 of even date, for hanger bracket.

The operation of my invention is as follows: 20 A cable 10 being extended across the upper side of the upper wall 16 of the channel hanger bar 11, said cable is detachably clamped upon said hanger bar by my spring clamp 1, with the clamp spring 3 extending longitudinally of the hanger bar 11 and engaging the under side of said bar; the spring arms 4 and 5 extending laterally from the ends of said spring under the lower edges of the side walls 17 of the hanger bar; the vertical arms 6 and 7 extending upwardly from the outer ends of the arms 4 and 5 over the outer sides of said side walls 17 of the channel hanger bar 11; and with the hooks 8 and 9 extending over the cable 10 in spaced relation and in opposite directions, which hooks are held in firm engagement 35 with said cable under pressure by the coil spring 3 which has a tendency to unwind and draw said hooks downwardly upon the cable 10 and said cable upon the hanger bar 11. In applying my clamp to a cable and a hanger bar, the cable 10 being extended over the hanger bar, one of the hooks 8 is extended over the cable 10 with the arm 6, forming the shank of said hook, extending downwardly over a side wall 17 of the hanger bar 11; the arm 4 extending inwardly from said arm 45 6 under the lower edge of said side wall 17 of the hanger bar and under the hanger bar to the lower side of the expanded spring 3; with the arm 5 extending from the upper side of the spring against the under side of the upper wall 16 of the hanger bar, and with the arm 7 with the hook 9 extending downwardly from the arm 5, as shown in Fig. 5 of the drawing. The arm 7 being gripped, said arm and hook 9, and the arm 5 are swung counterclockwise winding the spring 3 50 until the arm 5 is swung outwardly under the

lower edge of the other side wall 17 of the hanger bar; the arm 7 is swung upwardly over said side wall, and the hook 9 is swung upwardly over the cable 10 into engagement with the upper side of said cable, thus clamping the cable on the hanger bar with my clamp, as shown in Fig. 4 of the drawing.

We claim:

A spring clamp including a single elongated coil spring with its end extensions extending outwardly tangentially therefrom in parallel relation, and bent at right angles in opposite directions toward the spring axis and bent again in planes at right angles to the planes of the extensions and toward the spring forming arcuate cable hooks from the outer ends of said extensions.

ARLEY D. CARPENTER.
JOHN A. CARPENTER.
